CLAIM

The ornamental design for a suction cup mount with multi-part stalk, as shown and described.

DESCRIPTION

FIG. 1 is a front perspective view showing a suction cup mount with multi-part stalk of the present invention;

FIG. 2 is a front view thereof;

FIG. 3 is a right side view thereof;

FIG. 4 is a top view thereof;

FIG. 5 is a bottom view thereof;

FIG. 6 is a left side view thereof; and,

FIG. 7 is rear view thereof.

In the drawings, the broken line showings are for purposes of illustrating environmental structure or portions of the suction cup mount with multi-part stalk that form no part of the claimed design.
